UNITED STATES PATENT OFFICE.

AUGUST F. TRETER, OF TOLEDO, OHIO.

ANTICREEPING DEVICE FOR RAILS.

No. 919,092.

Specification of Letters Patent. Patented April 20, 1909.

Application filed January 20, 1909. Serial No. 473,369.

To all whom it may concern:

Be it known that I, AUGUST F. TRETER, citizen of the United States, residing at Toledo, in the county of Lucas and State of Ohio, have invented certain new and useful Improvements in Anticreeping Devices for Rails; and I do hereby declare the following to be a full, clear, and exact description of the invention, such as will enable others skilled in the art to which it appertains to make and use the same.

This invention has reference to an anticreeping device for rails, and it has for its object to provide a simple, inexpensive and effective device of this character which may be readily attached and detached and one in which the gripping action upon the rail may be increased as occasion may demand.

With this object in view the invention embodies certain novel features of construction and the combination and arrangement of parts hereinafter shown, described and specifically pointed out in the claims.

Referring to the accompanying drawings, Figure 1 is a plan view of a rail and my improved device in position to hold the same from creeping. Fig. 2 is an elevation of the same. Fig. 3 is a perspective of the device detached.

Referring to the drawings, 1 is a rail having the oppositely extending base flange 2, and 3 indicates a cross tie which supports the rail, the latter being spiked thereto in the usual manner.

Now referring particularly to my improved anti-creeping device, the same comprises crossed levers 4 and 5 pivoted together at 6 and each having a pair of upwardly extending gripping jaws 7 and 8 adapted to grip opposite sides of the base flange of the rail. The levers 4 and 5 are extended at 9 and 10

to overlie the cross tie and the end of each is provided with a downwardly extending lug as at 11 and 12 forming shoulders at 13 to abut against the tie and anchor the device against movement in the direction in which the rail has a tendency to creep, indicated by the arrow, Fig. 1. Lugs 11 and 12 are perforated to receive a transversely extending clamping bolt 14 by which the levers are drawn together to cause the gripping jaws to tightly grip the rail. When the device is in position, as shown in Figs. 1 and 2, the tightening of the clamping bolt will direct the strain upon the gripping jaws, the pivot which connects the levers being entirely free from strain. The device is quickly and easily applied to a rail and when in position effectively anchors the rail to the tie.

What I claim, is—

1. The combination with a rail, and a tie, of a pair of levers pivoted together and each provided with a pair of upwardly extending gripping jaws adapted to grip opposite sides of the base flange of the rail, and a clamping bolt to draw the free ends of the levers together, substantially as described.

2. The combination of a rail, and a tie, of a pair of pivoted levers each having a pair of gripping jaws engaging opposite sides of the base flange of the rail, the free ends of the levers provided with downwardly extending lugs which abut the tie, and a clamping bolt connecting the lugs to draw the levers together, substantially as described.

In testimony whereof, I hereunto affix my signature, in presence of two witnesses.

AUGUST F. TRETER.
